METHOD OF MAKING ELECTRICAL CONDENSERS

Application filed March 18, 1930, Serial No. 436,775, and in Germany May 25, 1929.

My invention relates to a method of making electrical condensers, particularly of small capacity, which is economical and offers increased dependability of service.

The invention is more particularly directed to the manufacture of condensers of small capacity such as are commonly used in radio receiving sets. According to the established practice for making such condensers, it is customary to stack upon each other alternate sheets of insulating material and conducting material or to wind strips of conducting material with interposed strips of dielectric material to a compact unit. Condensers of this kind, however, possess the disadvantage that it is necessary to provide means to keep the assembled sheets tightly together in order to prevent displacement of the dielectric in respect to the condenser armatures. Such displacement would entail changes in the capacity and is furthermore liable to give rise to flows in the dielectric and to a short circuit of the condenser.

I overcome these drawbacks by the novel method of making condensers as described by the present invention. To obtain this object, I propose to use a continuous strip of dielectric such as paper, celluloid, rubber, or what is known on the market as cellophane and the like, which is coated on both sides with a metallic layer. This strip is then sliced into a number of units corresponding to the size of the individual capacities. In order to prevent an increase of the leakage path from one condenser armature across the edge of the dielectric to the other armature caused by the cutting or slicing operation, a number of transverse sections at definite intervals of the continuous strip are left free from metallic coating as will be described in more detail.

Reference is made in the following description to the accompanying drawing, of which Figure 1 shows a strip of dielectric material provided with metallic coatings in accordance with my invention.

Figure 2 is a cross-section through a completed condenser as shown by Figure 3.

Figure 3 shows a finished individual con-

denser unit as sliced from a strip as shown by Figure 1, and

Figure 4 illustrates a single clamp which may be used for a condenser, as shown in Figure 3.

Similar reference numbers refer to identical parts throughout the different views of the drawing.

The dielectric strip 1 is coated on both sides by conducting layers 2 and 3 respectively. Such coating may be carried out according to any one of the well-known processes, such as, for instance, by means of a spraying process or by a so-called cathode disintegration process, or by means of an electrolytic process. The conducting layers are not applied over the entire surface of the dielectric, but a proper margin 6 is left free at opposite ends respectively, as seen from Figure 2. Furthermore, a number of transverse sections 5 are also left free from the metallic deposit at definite intervals corresponding to the desired capacity of the individual condenser units. These free sections and the margins 6 may be obtained by placing a stencil upon the dielectric sheet during the coating operation covering the space of the sections 5 as well as of the margin 6 and preventing a deposit of conducting material at these places.

Afterwards, the strip thus obtained is sliced across the sections 5 as indicated by dotted lines at A—A in Figure 1 and a corresponding number of individual condenser units obtained. The metallic layers 2 and 3 may then be connected in the usual manner to a clamp 6 and the whole surrounded by a casing 7 in order to protect the condenser against atmospheric influences. Figure 4 is a simple kind of clamp to be used in connection with the invention as shown, which consists of a connecting terminal 6 provided with flaps 8 which may be turned over by 180 degrees and bent around the edges of the condenser.

The further advantage of this method consists in that it is possible to use a very thin sheet of dielectric which insures the desired amount of capacity usually used in receiving sets by a condenser having two armatures only, such as illustrated. The providing of free sections 5 has the advantage that during

the slicing operation only insulating material is cut and not the metallic coating, which makes it impossible for metallic particles to be drawn by the cutting tool around the edge 5 of the insulating material, thus decreasing the creeping path between the condenser armatures and creating a defective condenser.

Although I have disclosed my invention with specific reference to the showing of the 10 drawing presented for purpose of illustration, I wish it to be understood that other forms are possible to practice the invention in conformity with the scope of the appended claims.

15 What I claim is:

1. The method of manufacturing electrical condensers which consists in coating a continuous strip of dielectric material at both sides with a metallic layer with transverse 20 sections at definite intervals left free from said coating and slicing said strips across said free sections.

2. The method of manufacturing electrical condensers which consists in coating a 25 continuous strip of dielectric material at both sides with a metallic layer, with a margin of both of the layers at opposite ends and a number of transverse sections at definite intervals left free from said coating, and afterwards slicing said strip into individual units across said free sections.

3. The method of manufacturing electrical condensers which consists in coating a continuous strip of dielectric material at both 35 sides with a metallic layer by an electrolytic process, with transverse sections at definite intervals left free from said coating, and slicing said strip across said free sections.

4. The method of manufacturing electrical condensers which consists in coating a continuous strip of dielectric material at both sides with a metallic layer by an electrolytic process, with a margin of both of said layers at opposite ends and a number 45 of transverse sections at definite intervals left free from said coating, and afterwards slicing said strip into individual units across said transverse sections.

5. The method of manufacturing electrical condensers which consists in applying to a continuous strip of dielectric material at both sides a metallic layer with transverse sections at definite intervals left free from said metallic layer and slicing said strips 55 across said free sections.

In testimony whereof I affix my signature.

WILHELM SCHEPPMANN.
